APPARATUS FOR HANDLING COAL

Max A. Matthews, Columbus, Ohio, assignor to
 The Jeffrey Manufacturing Company, a corporation of Ohio

Application June 26, 1937, Serial No. 150,610

2 Claims. (Cl. 209—247)

This invention relates to apparatus for handling coal and an object of the invention is to provide for the delivery of different size ranges of coal to coal cars substantially free of undesirable slack.

Another object of the invention is to provide apparatus for screening coal with a minimum formation of slack after the coal has been picked to remove refuse.

Still another object of the invention is to provide a material handling apparatus in which material may be selectively delivered to a pair of conveyors one of which is preferably a mat screen conveyor.

Other objects of the invention will appear hereinafter, the novel features and combinations being set forth in the appended claims.

In the accompanying drawings.

Fig. 1 is a diagrammatic plan view of a system comprising my invention which may be utilized to carry out the method of my invention;

Figs. 2 and 3, placed end to end, show in elevation an important portion of the apparatus comprising my invention;

Fig. 4 is a plan view with parts cut away showing a combined feeder and screen comprising my invention;

Fig. 5 is a side elevational view of the device of Fig. 4;

Fig. 6 is a sectional elevational view taken on the line 6—6 of Fig. 4 looking in the direction of the arrows;

Fig. 7 is a sectional elevational view taken on the line 7—7 of Fig. 4 looking in the direction of the arrows; and

Fig. 8 is an enlarged detail showing the construction of the mat of my combined feeder and screen.

Referring first to Fig. 1 of the drawings, there is seen a schematic showing of a system comprising my invention which is an illustrated embodiment of one form of apparatus which may be employed to carry out the method also comprising my invention.

In said Fig. 1 a tipple is designated generally by the reference character 10 and comprises a building or housing of the usual type within which is a raw coal storage hopper 11 within which the coal, which is to be treated and loaded, is first received. A feeder 12 is provided to feed the raw coal from the hopper 11 to a shaking or sizing screen and feeder 13 by which the raw coal will be separated into four size ranges and delivered along four different paths. As here illustrated, the slack

coal is delivered to the slack conveyor 14 by which it is delivered to a slack chute 15 for delivery into a slack coal car. The next larger size range from the sizing screen 13 is delivered to the apron conveyor or nut picking table 16. This size range of coal is generally designated as nut coal. The next larger size range of coal is delivered by the sizing screen 13 to the egg picking table or apron conveyor 17. The largest size range of coal is delivered from the sizing screen 13 to the lump picking table or apron conveyor 18.

It will be understood that the picking tables 16, 17 and 18 are so constructed that pickers may watch the coal as it progresses over them and may manually remove any particles of refuse, such as shale or slate, and throw said refuse into adjacent chutes, seen at 19, 20 and 21 adjacent the picking tables 16, 17 and 18, respectively. There are groups of pairs of chutes 19, 20 and 21 adjacent each side of the picking tables 16, 17 and 18, respectively, thus providing for two pickers for each table, one on each side thereof. Said chutes 19, 20 and 21 all lead to a refuse scraper conveyor 22 which conveys the received refuse to a refuse bin 23.

Associated with the nut picking table 16 is a nut loading boom 24, the free end of which may be lowered and elevated to discharge the nut coal into a car without appreciable drop thereof. A small stationary screening chute 25 is interposed between the discharge end of the nut picking table 16 and the nut loading boom 24. This chute effects the transfer of the nut coal from the former to the latter, and at the same time effects the screening thereof to remove any slack. This slack is discharged to the upper run 39 of a transversely extending mixing conveyor 26 which leads ultimately to a reducing crusher 27. The bottom of the screen chute 25 is also formed as a gate valve which may be operated to discharge all of the material from the nut picking table 16 onto the mixing conveyor 26.

Associated with the egg picking table 17 is an egg loading boom 28 between which is interposed a re-screening conveyor 29. The construction of the egg picking table 17, egg loading boom 28 and re-screening conveyor 29 are illustrated in more complete detail in Figs. 2 and 3 of the drawings and will be described in full detail hereinafter.

Associated with the lump picking table 18 is a lump loading boom 30 between which is interposed a re-screening conveyor 31. The construc-

tion of the lump picking table 18, lump loading boom 30 and re-screening conveyor 31 are substantially the same as the egg picking table 17, egg loading boom 28 and re-screening conveyor 29, and thus it will be understood that the apparatus disclosed in Figs. 2 and 3 will also apply thereto as well.

Referring particularly to Figs. 2 and 3 of the drawings, it will be seen that the picking table 17 comprises a stationary frame portion 32 and a hinged boom 33 between which extends a continuous apron 34 which travels around head pulley 35 and tail pulley 36, the latter of which is driven from a motor 37.

The picking table 17 receives a predetermined size range of coal from the sizing screen 13 which is discharged from the hinged boom 33 either to a chute 38 leading to the upper run 39 of mixing conveyor 26, as illustrated in full lines in Figs. 2 and 3, or directly to the re-screening conveyor 29, the detailed structure of which is illustrated in Figs. 4, 5, 6 and 7 and hereinafter described in detail.

Said re-screening conveyor 29 is effective to screen the coal and discharge the slack into the lower run 40 of the mixing conveyor 26 and to deliver the larger particles of coal onto the loading boom 28. Said loading boom 28 includes a stationary portion 41 and a pivoted loading portion 42 with a tail pulley 43 carried by the former and a head pulley 44 carried by the latter. A continuous apron 45 extends between the pulleys 43 and 44. An electric motor 46 is provided to drive the apron 45, which motor also drives the drive shaft 47 of the re-screening conveyor 29.

It is evident that with the boom 33 in the full line position illustrated in Figs. 2 and 3 of the drawings, coal from the picking table 17 will be delivered to the upper run 39 of the mixing conveyor 26. A similar condition may also be realized with the picking table 18. It is also evident that all material delivered to the upper run 39 of the mixing conveyor 26 will be conveyed to the right, as viewed in Fig. 1, leading to the crusher 27. However, the trough associated with the upper run of said mixing conveyor 26 is provided with appropriate valve means above each of the re-screening conveyors 29 and 31 that are associated with re-screening conveyor 29 being seen at 126 in Fig. 2 of the drawings. As a consequence, it is possible to discharge any material fed to the upper run 39 of the mixing conveyor 26 to the left of either of the re-screening conveyors 29 and 31 onto a selected one of said re-screening conveyors 29 or 31. For example, by opening the previously mentioned valve associated with the screening chute 25, the entire discharge of the nut picking table 16 may be delivered to the upper run 39 of the mixing conveyor 26. Said mixing conveyor 26 will then convey the material to the right, as viewed in Fig. 1. This material may then be discharged either to the re-screening conveyor 29 or the re-screening conveyor 31, or may be discharged to neither and conveyed further and discharged through a valve 48 which leads to a domestic coal bin 49 by way of chute 50.

Still further, if desired, any material on the mixing conveyor may be delivered to the crusher 27 by which it is crushed and delivered to the lower run 40 of the mixing conveyor from which it may be discharged by an appropriate valve into the slack chute 15 or may be discharged onto a re-circulating crushed coal conveyor 51 by which

it will be returned to the input of the sizing screen 13.

It is thus evident that a very flexible system is provided in which various mixtures of nut, egg, lump and slack may be fed over the booms 28 and 30.

With the hinged boom 33 in the dotted line position illustrated in Figs. 2 and 3, the picked egg coal will be delivered directly to the re-screening conveyor 29 which is effective to screen out the slack and deliver it to the lower run 40 of the mixing conveyor 26 while delivering the larger particles of coal to the loading boom 28.

An important feature of my invention resides in the provision of the re-screening conveyor 29 in that this conveyor forms the double function of delivering material from the picking table 17 to the loading boom 28 and at the same time removes the slack therefrom by a substantially horizontal movement of the material with a result that the re-screened coal is fed to the loading boom 28 with a minimum of shock and jar so as not to produce any further slack as an incident to this treatment. It has been found in practice that where inclined stationary or shaking screens are employed to feed a loading boom such as the loading boom 28, the coal, in discharging from the end of the inclined screen or chute, strikes the apron of the loading boom with such a velocity that there is an appreciable formation of slack and thus the work of the re-screening device is substantially negatived. I have found by employing a substantially horizontal type of re-screening conveyor no appreciable slack is formed thereby with the result that the coal, such as egg or lump, or a mixture of the two, delivered to the car is substantially free from slack.

Attention is now directed particularly to Figs. 4, 5, 6 and 7 of the drawings, which illustrate in detail the construction of a preferred form of the re-screening conveyor 29, it being understood that the re-screening conveyor 31 is preferably of the same construction. Said re-screening conveyor 29 comprises a main frame 52 within which is journaled the aforementioned drive shaft 47 carrying a plurality of drive sprockets 53 (see Fig. 4), and an idler shaft 54 mounted upon chain adjusting devices 55 and provided with idler sprockets 56. It will be understood that there are two of the chain adjusting devices 55, one at each end of the shaft 54.

Extending between the shafts 47 and 54 and riding on the sprockets 53 and 56, is a continuous mat type of screen conveyor 57 formed by a plurality of malleable iron block links formed by integral side bars and end barrels, as best seen in Fig. 8, and attached to articulate about transversely extending rods 58, thus providing a trouble free and long life mat screen.

Positioned above the main frame 52 is a hopper 59 at the material receiving end of which is formed a stationary chute 60 within which is associated a pivoted chute 61 pivoted about bolts 62 and having arms 63 to swing said chute about the axes of bolts 62. The pivoted chute 61 is provided to permit the pivotal adjustment of the hinged boom 33, as illustrated in Figs. 2 and 3 of the drawings, the arms 63 cooperating with appropriate pins 64 carried by the hinged boom 33 to lift the chute 61 out of the path of travel of said hinged boom 33 when the latter is elevated. Due to the action of gravity the pivoted chute 61 will move into material receiving posi-

tion automatically upon the lowering of the hinged boom 33.

Adjacent the forward end of the hopper 59 is provided a very short and gradually inclined feed 5 chute 65 for discharging material from the re-screening conveyor 29 onto the apron 45 of the loading boom 28.

Adjacent the rear and bottom portion of the re-screening conveyor 29 I provide a hopper 66 10 which directs slack which passes through the openings afforded by the mat screen conveyor 57 into the lower run 40 of the mixing conveyor 26.

Associated with the upper run of the screen conveyor 57 I provide a valve means which may 15 be operated to shut off entirely or to regulate the amount of screening effected thereby. Said valve means comprises a stationary top plate 67 extending transversely completely between the side members of the main frame 52 and thus entirely 20 transversely of the hopper 59, as clearly illustrated in Fig. 7 of the drawings. Said plate 67 is positioned above a plurality of longitudinally extending bars 68 the outermost ones of which extend substantially the full length of the re-screening conveyor 29 while the others extend only approximately half the length thereof, and form a grizzly adjacent the front end thereof which operates to support the mat screen conveyor 57, as clearly illustrated in Fig. 4 of the 25 drawings. Said bars 68 are supported on transversely extending angle members 168 forming part of the main frame 52.

Positioned below the plate 67 and above the bars 68 is a longitudinally slidable plate 69 provided with racks 70, one adjacent each end, as clearly illustrated in Fig. 7 of the drawings.

Associated with the racks 70 are pinions 71 35 keyed to a shaft 72 journaled in the main frame 52 and provided with an operating hand wheel 73. It is evident that by rotating the hand wheel 73 40 the slide plate 69 may be adjusted longitudinally to cover up the grizzly formed by the bars 68 and thus to provide an entirely closed bottom for the hopper 59 or to provide an opening of adjustable 45 size for said hopper 59. This construction is particularly useful where an unsized coal is to be fed to a car, in which case no attempt is made to remove the slack. This is another feature 50 which extends even farther the flexibility of the system comprising my invention.

Referring particularly to Fig. 6 of the drawings, it will be seen that a supporting plate 74 is provided adjacent the front end of the re-screening conveyor 29 to support the lower run of the mat 55 screen 57 during the first portion of its return travel where any slack which has fallen through the upper run thereof will be scraped into the hopper 66. Substantially midway between the sides of the hopper 66 I provide a transversely 60 extending pipe 75 to support the mat screen 57 above which I position a wiper 76 to insure the removal of any material which may tend to adhere to the top surface of the lower run of said mat screen 57.

65 It may additionally be mentioned that the drive for the apron 45 and the mat screen 57 includes the motor 46, seen in Fig. 2, which drives a pulley 77 through a plurality of V-belts 78, said pulley 77 being mounted on a countershaft 79 70 which carries a spur gear 80 meshing with a large gear 81 mounted upon a drive shaft 82 upon which is mounted the tail pulley 43 of the loading boom 28. Appropriate chain and sprocket means 83 is provided for driving the drive shaft 47 of 75 the re-screening conveyor 29 from the shaft 82.

In the operation of the apparatus comprising my invention with the consequent realization of the method comprising my invention, raw coal stored in the hopper 11 is fed by the feeder 12 to the shaking or sizing screen and feeder 13 by 5 which it is separated into four different size ranges comprising slack, nut, egg and lump coal.

Slack coal is conveyed directly by slack conveyor 14 and slack chute 15 to a slack car. The nut coal, egg coal and lump coal are delivered 10 respectively to the nut picking table 16, the egg picking table 17 and the lump picking table 18.

As these various ranges of coal are conveyed over these several picking tables, operators or pickers will manually remove visible refuse, such as shale or slate, and throw it into one of the chutes 19, 20 or 21, by which it will be delivered to a refuse chute 22, and conveyed to a refuse bin 23.

From the picking tables 16, 17 and 18, or any of them selectively, the coal may be discharged either to the upper run 39 of the mixing conveyor 26 or to its respective loading boom, such as the loading booms 24, 28 and 30, over the screening devices 25, 29 and 31, respectively.

By virtue of the mixing conveyor 26 it is evident that a large multiplicity of combinations of size ranges may be combined on a single loading boom. As a typical illustration, the egg picking table 17 may discharge to the upper run 39 of the mixing conveyor 26 and by said upper run 39 discharge to the re-screening conveyor 31. At the same time lump coal from the picking table 18 may be discharged directly onto the re-screening conveyor 31. It is thus evident that there will be a mixture of both egg and lump coal on the re-screening conveyor 31 which will be loaded by it onto the lump loading boom 30. In this instance, a combination of egg and lump coal will be fed to the car positioned below the loading boom 30. At the same time, any slack delivered either from the mixing conveyor 26 or from the picking table 18 to the re-screening conveyor 31, will be screened out and discharged into the lower run 40 of the mixing conveyor 26, by which it will be conveyed to the slack chute 15.

If desired, the gate mechanism, including the 50 slide plate 69, associated with the re-screening device 31, will be closed, in which case any slack contained in the coal received by the re-screening device 31 will not be removed, but will be discharged onto the loading boom 30.

As another illustrative operation, it may be found that there is too much lump coal coming over and not enough nut coal. To remedy this 55 situation, the lump coal may be fed into the upper run 39 of the mixing conveyor 26 and delivered to the crusher 27 which will reduce it to a maximum size and discharge it to the lower run 40 of said mixing conveyor 26. Said 60 lower run 40 may thereafter be controlled to discharge into the re-circulating crushed coal conveyor 51 which will deliver the crushed coal to the sizing screen 13, the same as if it were raw coal, whereupon it will be distributed the 65 same as raw coal.

It is to be particularly noted that the re-screening conveyors 29 and 31 are of such construction that the coal is transferred substantially horizontally over them while the slack is 70 being removed and is discharged at a relatively low velocity onto the loading booms 28 and 30. This avoids any shock which is realized with a discharge of coal over an inclined screen chute or inclined shaking screen.

By virtue of this construction there is practically no production of slack after the coal is discharged from the re-screening conveyor 29 or 31, and thus when desired, the coal, such as egg or lump, is delivered to the car substantially free of slack. In general, it is not necessary to employ this precaution in connection with the nut coal because this coal is not of sufficient size to cause appreciable formation of slack even though discharged over an inclined chute type of screen. If desired, however, the re-screening device may also be employed in connection with the nut picking table and loading boom.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In combination, a horizontally disposed continuous travel mat screen, a conveyor positioned thereabove, an adjustable pivoted boom conveyor having an adjustable free discharge and positioned to feed said screen or said conveyor, and a feed chute pivoted to said screen and swingable by said pivoted boom into and out of feeding position as said boom is adjusted to feeding or non-feeding position with respect to said screen. 10

2. In combination, a pair of conveyors spaced vertically apart, the lower one being an endless mat screen conveyor, a pivoted boom having a freely adjustable discharge end adjustable to feed either conveyor, a pivoted chute for guiding material from said boom to said lower conveyor and positioned in the path of said boom during upward movement thereof, and means operable by said boom to pivot said chute and swing it out of the path of movement of said boom as the latter moves upwardly and to swing said chute into operative position as the boom moves downwardly. 15 20

MAX A. MATTHEWS.
